UNITED STATES PATENT OFFICE.

EDWARD KATZINGER, OF CHICAGO, ILLINOIS, ASSIGNOR TO EDWARD KATZINGER COMPANY, OF CHICAGO, ILLINOIS, A CORPORATION OF ILLINOIS.

BAKING OVEN.

Application filed January 15, 1920. Serial No. 351,582.

To all whom it may concern:

Be it known that I, EDWARD KATZINGER, a citizen of the United States, residing at Chicago, in the county of Cook and State 5 of Illinois, have invented certain new and useful Improvements in Baking Ovens, of which the following is a specification.

My invention relates to baking ovens and one of its objects is the provision of a simple and efficient oven for using heat economically.

A further object is the provision of such an oven with air passages in its walls for permitting air to pass into the oven and 15 absorb heat radiated to the walls of said oven.

Another object of the invention is the provision of air passages in a baking oven arranged to introduce air into the oven and 20 effect the combustion of unconsumed or partially consumed gases issuing from a gas heater and thereby effect the saving in the fuel supplied to such gas heater.

Other objects of the invention will appear 25 hereinafter, the novel features and combinations being set forth in the appended claims.

An embodiment of my invention is illustrated in the accompanying drawings, in 30 which

Fig. 1 is an end view of my improved baking oven with a portion broken away to show interior structure and inner parts;

Fig. 2 is a side view with a portion broken 35 away to show interior structure and inner parts; and

Fig. 3 is a transverse sectional elevation of a modification.

In the accompanying drawings I have 40 shown the oven proper mounted on end spaced-apart pedestals or supports 4 which are in the form of frames having front and back legs. Mounted on the supporting frames 4 are the open frames 5 which are 45 adapted to receive sheet metal closures to form the end walls 22 of the lower portion of the baking oven as shown in Fig. 2. In Figs. 1 and 2 I have shown semi-circular frames or castings with openings to receive 50 closures to form end walls at the upper portion of the oven respectively above the end frames 5 and the closures 22 thereof. A semi-cylindrical top, hereinafter more fully described, extends between the upper semi-circular edges of the frames 6. Each of the

frames 6 is provided with an ear 7 pivotally connected at 8 to an ear 9 on a frame 5. This construction permits the swinging of the semi-cylindrical top on a horizontal axis 8 in order to entirely open the oven when 60 desired.

In Figs. 1 and 2 flue openings 10 are shown one in each of the frames 6 at the upper portions thereof for connection to a chimney or flue in a well known manner. 65 When the baking oven is provided with a flat top as shown in Fig. 3 flue openings may be provided at the upper central portions of the end walls similar in construction to the flues 10 shown in Figs. 1 and 2.

In the construction shown in Figs. 1 and 2 the frames 5 are provided with bearings 11 to receive the shaft 12 of a carrier frame comprising such shaft 12 and the spaced-apart plates 13 connected to said shaft and 70 rotatable therewith. A plurality of pan shelves or baskets 14 are suspended from the rods 15 which rigidly connect the spaced-apart plates 13 at spaced-apart points around circumferences as shown in Fig. 1. 75 The carriers 14 comprise horizontal plates to the ends of which are connected vertical triangular plates loosely pivoted to the bars or rods 15 so that when the carrier frame comprising end plates 13 is rotated the 80 plates 14 will always occupy approximately horizontal positions.

It should be noted that the structure shown in Figs. 1 and 2 is such that the entire carrier mechanism including the carrier frame and the suspended carrier plates 14 may be lifted directly out of the oven after the semi-cylindrical cover comprising the end frames 6 has been tilted back on the hinges 8. It will thus be seen that during 90 the baking of the material on the shelves 14 the detachable carrier mechanism is entirely inclosed by the oven walls and therefore the heat will be confined as desired, and furthermore the entire carrier mechanism with 95 all of the baked material still supported thereby may be quickly removed from the oven and replaced by another carrier mechanism with unbaked material on its shelves, and the cover closed without altering materially previous adjustments of the baking oven apparatus. The hinged cover and detachable carrier mechanism also facilitate 100 removal of the carrier mechanism for the purposes of repair, while another carrier 105 carrier 110

mechanism is placed in the oven so that use of the latter may be continued.

The bottom or floor 16 of the oven shown in Figs. 1 and 2 is provided with flaring edges 5 at a longitudinal opening 17 in position to receive the heat from a plurality of spaced-apart gas burners 18 connected to a supply pipe 20 and each provided with a controlling valve 19. While I prefer to use 10 gas burners to consume gas as a fuel for providing heat in the oven it is obvious that other heating mediums may be used if so desired.

In order to more evenly distribute the heat 15 in the oven I have shown a horizontal baffle plate 21 in Fig. 1 above the opening 17 in a plane spaced above the floor 16 of the oven. Figs. 2 and 3 omit such a spreading plate or baffle plate.

20 In Fig 1 I have shown the front and back upright walls so constructed as to afford air passages leading from the front and rear bottom edges of the walls at 25 upwardly and downwardly into the oven at 26 near 25 the floor 16. These walls are shown as constructed of outer and inner spaced-apart vertical plates 22 and 23 with an intervening spaced partition 24 over the upper edge of which the air may pass from the outer 30 opening 25 to the inner opening 26. The openings 25 are located between the lower edges of the outer plates 22 and the lower edges of the partitions 24 and these openings 25 permit the air from the outside atmosphere to enter the passages of the walls. The partitions 24 are shorter than the plates 22 so that openings may be afforded over the tops of the partitions to the openings 26. The end walls may also be provided 35 with such air passages for directing a supply of air from the outside to the interior of the oven as shown by the arrows at the right hand portion of Fig. 2.

In Figs. 1 and 2 I have shown a longitudinal door 27 extending substantially the 45 entire length of the oven and hinged at 28, so as to afford access to the interior of the oven. When desired the door 27 may be opened and material placed on or taken off 50 the shelves 14 one after another, the carrier mechanism being rotated manually by grasping the rods 15.

The door 27 preferably comprises spaced-apart cover plates with heat insulating material, such as asbestos, between such plates. Other portions of the oven wall construction may also be provided with heat insulating material between spaced-apart plates. For instance in Fig. 2 I have shown the 55 semi-cylindrical top and the end walls thereof provided with spaced-apart plates 30 with heat insulating material, such as asbestos, between them.

In order that the progress of the baking 60 operation may be observed without opening

the door 27 or opening the semi-cylindrical cover one or more windows 32 of transparent material may be provided at a convenient location such as in the semi-cylindrical cover as shown in Fig. 1 or in the wall above 75 the door 27 as shown in Fig. 3.

Preferably the carrier mechanism for supporting the material to be baked is such as to distribute such material to various parts of the oven so that a maximum space in the 75 oven will be available for baking purposes without interfering with the free circulation of the heat around the material to be baked. In the operation of the baking oven the heat is generated at the burners 18 and 80 this heat passes up around the shelves 14 to effect the baking of materials thereon.

In Fig. 3 I have shown the inner edges of the floor plate 16 flared upwardly and toward the burner 18 so as to assist in directing a continual supply of fresh air to these burners.

The chimney openings 10 are preferably controlled by dampers, not shown, so as to regulate the passage of the air to the burners 90 and the gaseous products of combustion through the oven.

As the oven heats up the heat tends to radiate through the walls but this is greatly retarded by the insulating material 31 therein. Such radiation of heat is also greatly retarded through the air passage walls because the draft is upward through the oven to the flue openings 10 which causes air to be drawn through the passages into the interior of the oven thereby causing the heat in such air passages to re-enter the oven. That is to say, the draft in the oven toward the flue openings 10 causes the heat absorbed by the air in hollow walls to enter the oven 105 at the openings 26 instead of being radiated to the outside atmosphere.

However, the wall passages have another important function in that they effect the pre-heating of the air flowing through such wall passages before such air enters the oven thereby putting such air entering through such passages in condition to afford more complete combustion of the unconsumed gases and the partially consumed gases from the gas burners. I have found from actual 110 experience that baking ovens provided with such wall passages as herein disclosed may be practically operated with a considerable decrease in the consumption of gas and with substantially no odor whatever due to the use of gas as a heating fuel.

During such practical operation the dampers may be partially closed, the gas burners turned down after the oven has been heated up, and great 120 efficiency in baking obtained by the equal distribution of the heat due to greater efficiency in the consumption of the gas which is effected by the supply of the pre-heated air from the outside atmosphere through 125 130

the bottom edges of the upright walls to the interior of the oven and mixture with the unconsumed gases, or partially consumed gases such as carbon monoxide.

5 In Fig. 3 I have shown coverings of tiles 34 on the outside of the upright and top walls, with openings in the covering of the front wall for the window 32 and the door 27. Such coverings may be placed on the 10 oven in whatever shape the oven may be made.

Obviously those skilled in the art may make various changes in the details and arrangement of parts without departing from 15 the spirit and scope of my invention as defined by the claims hereto appended and I wish therefore not to be restricted to the precise construction herein disclosed.

What I wish to have protected by Letters 20 Patent of the United States is:—

1. An oven comprising an enclosing casing having a hollow wall with a passage leading upwardly from the outside atmosphere and thence downwardly into the 25 interior of such casing.

2. A baking oven comprising a pre-heating chamber for air entering said oven from the outside atmosphere, said oven being provided with an additional opening in its bottom wall for receiving a gaseous heating 30 medium.

3. A baking oven comprising an enclosure adapted to receive through an opening in its under side a heating medium and provided in its wall structure with a pre-heating 35 chamber for directing air from the outside atmosphere through such wall structure into the interior of said enclosure at a position spaced from the place where the 40 heating medium is introduced.

4. The combination with an oven comprising a casing having an upright wall with an air passage leading from the outside atmosphere to the interior of said casing upwardly through such wall, and burner mechanism at an opening extending through the 45 bottom of said casing.

5. An oven having a portion thereof provided with outer and inner spaced-apart 50 walls, and an intermediate partition to afford an air passage from the outside atmosphere adjacent the lower edge of the outer wall, upwardly over said partition and downwardly beneath the lower edge of said 55 inner wall into the interior of the oven.

6. An oven comprising a casing having an upright wall provided with inner and outer sections with a partition spaced therebetween to afford a circuitous passage from 60 the outside atmosphere to the interior of said casing.

7. In a baking oven, the combination with 65 upright walls having vertically extending circuitous passages therein and sealed at their tops, of a curved top forming a cover

resting on said walls, and carrier mechanism within the oven but removable when said cover is opened.

8. In a baking oven, the combination with upright walls having vertically extending 70 circuitous passages therein and sealed at their tops, of a semi-cylindrical top resting on said walls and forming a cover for the oven, a pivotal connection between such cover and one of the walls, and carrier mechanism detachably mounted in said oven and removable therefrom when said cover is tilted back on said pivotal connection.

9. An oven comprising a hollow upright wall with a partition and openings affording a passage extending a plurality of times substantially throughout the height of said wall and leading from the outside atmosphere to the interior of the oven.

10. An oven comprising a casing having 85 in some portions thereof spaced-apart plates with stationary heat insulating material between such plates, and having in other portions thereof spaced-apart plates with an intermediate partition and openings to afford a circuitous air passage from the outside atmosphere upwardly and then downwardly into the interior of the oven.

11. An oven having an upright wall with an air passage extending over substantially 90 the entire area of said wall within the same from the bottom thereof to the top thereof and with an additional air passage also extending over substantially the entire area of said wall within the same from the top 95 thereof to the bottom thereof, said area air passages establishing a communication between the outside atmosphere upwardly and downwardly through said wall to the interior of the oven.

12. An oven comprising a casing with an upright wall having air passages extending from substantially the top of said upright wall to the bottom thereof to afford a flow of air from the outside atmosphere upwardly to the top of said wall and thence downwardly into the interior of said oven.

13. An oven comprising a casing having a portion thereof provided with an upright wall with air passages therein for introducing air into said oven from the outside atmosphere, means for introducing heat into said oven through an opening in the bottom of the latter, and a heat insulating covering 115 for said casing.

14. An oven comprising a casing, a plurality of shelves for supporting the material to be baked distributed in the space within said casing, means for generating heat in the oven and wall structure for introducing air 125 into the oven from the outside atmosphere distant from said heat generating means through passages extending back and forth and generally vertically.

15. An oven comprising upright walls 130

having circuitous passages therethrough leading from the outside atmosphere to the interior of the oven, movable carrier mechanism comprising pivotally mounted shelves 5 for supporting the material to be baked in distributed positions in the oven, and means for introducing heat into the oven through an opening in the bottom of the latter.

16. An oven comprising hollow upright 10 walls with passages therein for leading air from the outside atmosphere up and down through such walls into the interior of said oven, means for introducing heat into the oven, and a plurality of supports for the 15 baking material to carry the latter at various elevations and in distributed relation in the space in the oven.

17. An oven comprising a casing having a slot in the bottom thereof, heat generating 20 means for the oven extending through said slot, wall structure for introducing air from the outside atmosphere into the oven distant from said heat generating means, and traveling carrier mechanism within said oven.

25. 18. An oven comprising a casing having hollow walls with passages leading back and forth vertically from the outside atmosphere into the interior of said oven, means for introducing heat into the oven, and 30 traveling carrier mechanism comprising a plurality of pans in spaced-apart relation and pivotally suspended to occupy substantially horizontal positions when moved to various parts of the space within the oven.

19. An oven comprising hollow walls having circuitous passages leading back and forth therethrough vertically from the outside atmosphere to the interior of the oven, means at the bottom of the oven for the introduction of heat into the oven, and traveling carrier mechanism adapted to bring the baking material successively past the heat introducing means and the space where the pre-heated air is being introduced into the oven from said hollow walls. 35

20. An oven comprising enclosing walls with a slot in the central portion of its bottom walls and a circuitous passage in an upright wall opening near the bottom toward said slot, deflectors along said slot inclined 40 toward each other, and heat-producing means in the oven adjacent said slot. 45

21. An oven comprising enclosing walls with a slot in the central portion of the bottom wall and a circuitous passage in its upright wall leading from the bottom of said wall upwardly and then downwardly and opening toward said slot near the bottom wall, burners extending through said slot and disposed above the bottom wall of the oven, and deflectors inclined toward and having their top edges lower than said burners. 55

In testimony whereof I have signed my name to this specification on this 13th day 60 of January A. D., 1920. 65

EDWARD KATZINGER.
